COLLOID MILL

Louie H. Morehouse, Los Angeles, Calif.

Application March 23, 1936, Serial No. 70,233

1 Claim. (Cl. 83—7)

This invention relates to a mill and more particularly pertains to mills of that class employed in the formation of colloidal or paste products by the minute disintegration of solids suspended in liquids.

An object of the invention is to provide a mill embodying a grinding rotor associated with a grinding stator between which a mixture of solid particles and a liquid are passed either by gravity feed or under pressure to effect grinding and mixing of the materials, in which the rotor is so mounted that it may be readily adjusted relative to the stator to control the degree of fineness to which the solids are disintegrated and also to compensate for wear of the grinding surfaces.

Another object is to provide a mill of the type including a horizontally revoluble grinding rotor carried on the upper end portion of a vertical shaft and arranged in juxtaposition with the under side of a stator in which the rotor and shaft is carried in a mounting constructed for effecting vertical adjustment thereof, and in which the mounting includes roller bearings together with means for forcing lubrication of the bearings so formed and arranged as to insure against any lubricant being brought into contact with the products of the mill.

A further object is to provide a mill embodying the above features in which the parts are so formed and arranged as to facilitate their assemblage and demounting thereof.

With the foregoing objects in view together with such other objects and advantages as may subsequently appear the invention is carried into effect as hereinafter described and claimed and as illustrated for example in the accompanying drawing in which:

Fig. 1 is a view of the mill as seen in vertical section with parts shown in elevation;

Fig. 2 is a horizontal section taken on the line 2—2 of Fig. 1;

Fig. 3 is a detail in vertical section taken on the line 3—3 of Fig. 1;

Fig. 4 is an enlarged section taken on the line 4—4 of Fig. 1.

Referring to the drawing more specifically A indicates generally the pedestal portion of the mill, the base of which is carried by any suitable support. The upper portion of the pedestal A is formed with a spill-way B embodying a cylindrical side wall 6 and an inclined bottom wall 7; the portion of the side wall 6 adjacent the lower end of the bottom wall 7 being formed with an outlet opening 8. Mounted on the upper margin of the

pedestal A is a cap C formed with a marginal flange 9 which seats on the upper edge of the cylindrical wall 6; the cap being demountably and rigidly fastened in place on the pedestal by bolts 10 engaging lugs 11 on the adjacent marginal 5 portions of the cap and pedestal.

Formed on the under side of the cap C is a recess 14 in which is seated an annular stator grinder D which is demountably and rigidly held in place on the cap C by an annulus 15 secured 10 to the under side of the cap C by screws 16 which annulus is arranged with its inner margin overlying the lower outer marginal portion of the stator grinder D. The inner annular margin of the stator D is inclined outwardly and downwardly to form a beveled grinding face 17.

A rotor grinder E is arranged beneath the stator D and has a frustro-conical extension 18 which projects upwardly into the space bounded by the inclined inner margin of the stator D. 20 The extension 18 has an inclined face 19 at the base portion thereof conforming to the lower portion of the inclined surface 17 of the stator D, while the upper portion of the rotor extension 18 converges at an angle relative to the inclined 25 face 17 to afford a V-channel 20 between the upper inner marginal portion of the stator and the contiguous upper portion of the rotor to facilitate the feeding of materials to be ground between the grinding surfaces of the rotor and 30 stator.

The cap C is formed with a chamber 21 which opens to the channel 20 and is formed with an intake opening 22 leading to the chamber 21 through which materials to be ground are delivered to the chamber and to the grinding rotor and stator; the opening 22 being internally threaded for connection with a feed pipe, not shown, through which the materials may be fed either by gravity flow or under pressure.

The rotor E is carried on a disk shaped base plate 23 having an upstanding marginal flange 24 which encircles the outer periphery of the rotor grinder E; the base plate and the rotor grinder being formed with a central opening to 45 receive the upper end portion 25 of a vertical revoluble shaft F journaled on and extending axially through pedestal A.

In carrying out the invention the pedestal A is formed with an open ended tube 26 extending 50 vertically through the inclined bottom wall 7 of the spill-way B; the upper end of the tube terminating on a plane intermediate the margin of the cylindrical wall 6 and the inclined bottom wall of the spill-way and the lower end thereof 55

terminating adjacent the under side of the inclined bottom wall 7.

Extending into the upper end of the tube 26 is a cylindrical jacket 27 having at its upper end a marginal flange 28 which seats on the tube 26. This jacket 27 is formed with an internally threaded lower end portion into which is screwed for vertical adjustment a tubular sleeve 29, the lower end of which projects downwardly through the tube 26 and terminates below the lower end of the latter. A flange 30, constituting a wrench hold, is formed on the lower end of the sleeve 29 for facilitating turning of the sleeve to advance or retract it longitudinally on its threaded connection with the jacket 27. As here shown the flange 30 is formed with radially extending openings 31 for the reception of a lever or other suitable tool for effecting rotation of the sleeve. The pedestal A is formed with a side opening 32 to give access to the flanged lower end of the sleeve 29.

The upper end of the sleeve 29 terminates in inwardly spaced relation to the upper end of the jacket 27 and seating thereon is the outer race member *a* of a ball bearing 33, the inner race member *b* of which bearing is affixed to the shaft F which extends upwardly through the sleeve 29; the shaft being formed with a shoulder *c* on which the race member *b* seats. A collar 34 is screwed onto the upper end portion of the shaft F and bears on the bearing member *b* to clamp the latter tightly in place against the shoulder *c*. Balls *d* are arranged between the race members *a* and *b* in the usual manner to afford a roll bearing for the shaft F.

The upper end of the collar 34 affords a seat for the base plate 23 of the rotor D and is formed with openings 35 into which extend pins 36 carried by the plate 23 to hold the latter against rotation relative to the collar 34; the upper end of the shaft 25 being fitted with a clamping nut 37 screwed thereon for clamping the rotor and its base plate firmly in place on the collar 34.

An important feature of the invention resides in forming the upper end of the sleeve 29 with an annular well 38 for containing a liquid lubricant, and in providing means for conveying lubricant from the well 38 to the bearing 33 thereabove. This lubricating means embodies a ring 39 rigidly fixed to the shaft F beneath the bearing 33 and projecting from the shaft over the well 38 and on which ring is mounted a series of depending tubes 40 which extend downwardly into the lubricant in the well 38; the upper ends of the tubes opening to the space between the rings *a* and *b* of the bearing 33, and the lower ends thereof being turned to open in the direction of rotation of the shaft F, whereby on rotation of the shaft F a forced delivery of lubricant from the well 38 to the bearing 33 will be effected.

As a means for preventing discharge of the lubricant into the spill-way B a seal G is provided in the space between the jacket 27 and the collar 34 which seal embodies a ring 42 carried on the jacket 27, packing rings 43 supported on the ring 42, a crowding ring 44 seating on the packing rings 43, and a split ring 45 seating in a circumferentially extending groove on the inner periphery of the jacket 27 adjacent the upper end thereof; the split ring 45 engaging the upper outer marginal portion of the ring 44 to hold the assembled packing in place.

As a means for holding the jacket 27 and sleeve 29 against rotation relative to each other and also holding the jacket 27 against turning in the tube 26, a set screw 46 is provided having an enlarged

shank which leads through aligned openings 47 and 48 in the walls of the pedestal A and tube 26, and is threaded through the jacket 27 into abutting engagement with the sleeve 29.

In assembling the mill several procedures may be employed one of which consists in initially assembling the jacket 27 and sleeve 29 by screwing them together, then lowering this assembly into the tube 26 to the seated position of the jacket with lubricant contained in the well 38. A section of the shaft F carrying the bearing 33 and the ring 39 with the tubes 40 thereon, is then passed downwardly through the sleeve 29 to position the bearing 33 on the upper end of the sleeve and with the tubes 40 extending into the lubricant in the well 38. The packing seal G is then assembled in the jacket 27 whereupon the collar 34 is screwed in place on the shaft and brought to bear on the inner ring *b* of the bearing 33. The assembled grinding rotor 24 and base plate 23 is then applied to the shaft with the pins 36 engaging the openings 35 whereupon the clamping nut 37 is screwed on the upper end portion of the shaft to clamp the rotor in place. The cap C carrying the stator D is then set in place on the pedestal and secured thereto by the bolts 10.

Vertical adjustment of the shaft F is effected by rotating the sleeve 29 to advance it longitudinally in the jacket 27 whereby the shaft is shifted vertically to bring the grinding surface 19 of the rotor into desired proximity to the grinding surface 17 of the stator; vertical movement of the sleeve 29 serving to effect corresponding movement of the shaft F since the sleeve serves as a mounting for the shaft by reason of the latter being supported thereon through the medium of the bearing 33.

During adjustment of the sleeve 29 the jacket 27 is held in place by the screw 46 which is engaged therewith but is retracted relative to the sleeve 29. After having effected the desired adjustment the screw 46 is set to engage the sleeve 29 thereby holding the latter against rotation relative to the jacket 27.

The lower end of the shaft F is then affixed to a driving section 49 by means of a sleeve 50 fastened to the shaft F by a set screw 51 and having splined connection to the shaft 49 by spline 52 which permits vertical adjustment of the shaft F relative to the shaft 49.

In effecting a grinding action the shaft with the assembled rotor is revolved and the materials to be worked, usually comprising granular solids suspended in liquid, are delivered to the chamber 21 in the cap C and into the feed channel 20 from which the materials pass between the grinding surface 17 and 19 and are there subjected to the desired grinding action; the ground materials being ejected by centrifugal force from the rim of the rotor and delivered to the spill-way B from which they pass to discharge down the incline bottom wall and through the opening 8. During rotation of the shaft F the bearings 33 are maintained lubricated by the action of the tubes 40 as before described, the lubricant being directed into the spaces between the balls *d* to effect lubrication thereof; the lubricant being confined within the jacket 27 by the seal G and thus prevented from coming into contact with the products of the mill.

It will be seen from the foregoing that by loosening the bolt 46 and turning the sleeve 29 the rotor may be easily and quickly adjusted relative to the stator so as to maintain their contiguous grinding surface in proper relation to

each other according to the grade of products desired. By supporting the bearing 33 on the shaft F and providing the splined connection between shaft F and its driving section 49 such adjustment 5 may be effected while the mill is in operation; the sleeve 29 being turnable independent of the shaft F and operating on being advanced into the jacket 27 to move the bearing 33, shaft F, and rotor to an elevated position as indicated by 10 the dotted lines f in Fig. 3.

I claim:

In a colloid mill, a pedestal formed with a spill-way in its upper portion having an inclined bottom wall, an open ended tube extending vertically through said bottom wall, a jacket 15 extending into and supported by said tube formed

with an internally threaded end portion, a sleeve extending into the lower end of said jacket having screw engagement therewith, a set screw having threaded engagement with said jacket for engaging said sleeve to hold the sleeve against turning in said jacket, said set screw having a shank extending through openings in said tube and pedestal to hold said jacket against turning in said tube, a shaft extending through said sleeve having its upper end portion projecting above 10 said jacket and tube, a grinding rotor carried on the upper end portion of said shaft, and an annular grinding stator affixed on said pedestal arranged above said rotor and formed to cooperate with said grinding rotor. 15
